H. R. McCONNELL

CHUCK

Filed Nov. 7, 1922

Inventor

Harry R. McConnell,

By Ch. Parkin

Attorney

UNITED STATES PATENT OFFICE.

HARRY R. McCONNELL, OF RICHMOND, VIRGINIA, ASSIGNOR TO THE McCONNELL-BROWNING ENGINEERING COMPANY, OF RICHMOND, VIRGINIA, A CORPORATION OF VIRGINIA.

CHUCK.

Application filed November 7, 1922. Serial No. 599,587.

To all whom it may concern:

Be it known that I, HARRY R. McCONNELL, a citizen of the United States, residing at Richmond, in the county of Henrico and 5 State of Virginia, have invented certain new and useful Improvements in Chucks, of which the following is a specification.

This invention relates to chucks and more particularly to such a device provided with 10 gripping elements adapted to be clamped about the shank of a tool and having actuating means whereby the gripping element may be easily and rapidly advanced into loose engagement with the tool, 15 supplementary means being provided for tightly clamping the gripping elements about the tool.

In the chucks now commonly employed a plurality of gripping elements are employed 20 having thread sections formed in their outer faces engaged by an internally threaded rotatable ring whereby they may be moved into engagement with the tool. In such chucks but a single actuating means is 25 employed for moving the gripping elements, and if the threads employed are of slight pitch so that the tool may be tightly clamped with little likelihood of becoming loose during the operation of the chucks it requires a 30 number of turns of the sleeve to move the gripping elements a relatively short distance with a consequent loss of time. It is the usual practice therefore to provide relatively high pitch threads whereby the gripping 35 elements may be rapidly moved into engagement with the tool, but the use of such a construction results in the frequent loosening of the gripping elements.

In a copending application, Serial No. 40 591,586, filed September 20th, 1922, I have disclosed a chuck having an actuating ring for moving the clamping elements into engagement with the tool wherein high pitch threads are employed for rapidity in action, 45 the ring being adapted to partake of limited longitudinal movement, further means being provided for moving the ring longitudinally to tightly clamp the gripping elements in position without danger of becoming loose 50 during operation. The present invention is an improvement over my copending application above mentioned, being simple in construction, and being so designed as to permit the supplementary clamping means to be

readily operated without the use of a wrench 55 or other tool.

It is an important object of the present invention to provide main actuating means for moving the clamping elements into loose engagement with the tool and to provide 60 novel means for tightly clamping the gripping elements about the tool, anti-friction means being employed whereby an extremely tight clamping action may be obtained by manual operation without the 65 use of tools.

Other objects and advantages of this invention will be apparent from the course of the following description.

In the drawings I have shown one embodiment of the invention. In this showing,

Figure 1 is a side elevation of a chuck embodying the invention,

Figure 2 is a central longitudinal sectional view taken substantially on line 75 2-2 of Figure 5,

Figure 3 is a detail view of one of the clamping elements,

Figure 4 is a side elevation of the body 80 portion of the device,

Figure 5 is a section taken on line 5-5 of Figure 2,

Figure 6 is a sectional view taken on line 6-6 of Figure 2, and,

Figure 7 is a bottom plan view of the cap. 85

Referring to the drawings, the numeral 10 designates the body portion of the device as a whole, mounted upon a rotatable spindle 11 driven by a drill press or other machine. The body portion 10 terminates in a tapered 90 lower end 12 and is provided with a plurality of downwardly converging openings 13 in which are mounted gripping elements.

14. The gripping elements are provided with clamping faces 15 as shown in Figure 95

2. The upper ends 16 of the gripping elements are reduced as shown and are provided with relatively high pitch threads 17 as shown in Figures 2 and 3.

The body portion 10 is provided intermediate its ends with an annular groove 18 communicating with the openings 13. A ring 19 is mounted in the groove 18, being split as at 20 to permit it to be placed in the groove when the device is assembled. 100 The ring 19 is provided with internal threads 21 engaging the threads 17 of the clamping element. A sleeve 22 surrounds

the ring 19 as shown in Figure 2, having a driving fit therewith whereby rotation of the sleeve will cause rotation of the ring to move the gripping elements as will be obvious. As shown in Figure 2, the ring 19 is of a width somewhat less than the width of the groove 18 whereby limited longitudinal movement of the ring and the sleeve 22 is permitted.

10. A rotatable sleeve 23 surrounds the body portion 10 intermediate the sleeve 22 and the upper end of the body portion. The sleeve 23 is provided adjacent its lower end with a ball race 24 having antifriction balls 25 therein which contact with the upper face of the ring 19. The upper face of the sleeve 23 slopes inwardly and downwardly as shown in Figure 2 and is provided with a plurality of convolute grooves 26 of arcuate cross-section for a purpose to be described. The upper end of the sleeve 23 is provided with an annular extension 27 having a lug 28 projecting upwardly therefrom.
15. The upper end of the body portion 10 is threaded as at 29 for the reception of a cap 30 having an internal shoulder 31 adapted to contact with the upper end of the body portion. When the cap 30 is placed in position it is screwed down tightly with the shoulder 31 in firm engagement with the upper end of the body portion whereby the cap forms in effect a part of the body portion. As shown in Figure 2, the lower portion of the cap is arranged within the extension 27 of the sleeve 23 and has an arcuate extension 32 arranged in the path of travel of the lug 28 whereby rotational movement of the sleeve 23 is limited. As shown in Figure 7, the cap 30 has its lower face arranged substantially at right angles to the axis of the body portion and provided with a plurality of arcuate convolute grooves 33. When the device is assembled the lower face of the cap 30 is arranged adjacent the upper face of the sleeve 23 and the grooves 33 extend oppositely to the grooves 26, antifriction balls 34 being arranged in the grooves at their points of intersection, as shown in Figure 6. It will be apparent that when the sleeve 23 is rotated the ball receiving portion of the grooves 26 and 33 move toward or away from the center.
20. The operation of the device is as follows:

- When it is desired to insert the shank of a tool within the gripping elements, the sleeve 23 is rotated to move the balls 34 toward the center. The sleeve 22 is then rotated to rapidly move the gripping elements downwardly and inwardly into engagement with the tool. The sleeve 23 is then rotated to move the balls 34 outwardly and the inclination of the upper face of

the sleeve 23 causes the latter to move downwardly. The balls 25, contacting with the upper face of the ring 19, cause the latter to move downwardly whereby the gripping elements are clamped tightly about the tool. It has been found that the arrangement of the antifriction balls 25 and 34 permits the gripping elements to be clamped tightly about the tool so that they do not become loose during the operation of the chuck.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A chuck comprising a body portion, means carried thereby for gripping a tool, actuating means for moving said gripping means into loose engagement with the tool, a rotatable sleeve engaging said actuating means and provided with a cam, and an antifriction element mounted between said cam and said body portion to move said gripping elements into firm engagement with the tool upon rotation of said sleeve.

2. A chuck comprising a body portion, means carried thereby for gripping a tool, actuating means for moving said gripping means into loose engagement with the tool, a rotatable sleeve engaging said actuating means and provided with an enclosed cam groove, and an antifriction ball mounted between said cam groove and said body portion to move said gripping elements into firm engagement with the tool upon rotation of said sleeve.

3. A chuck comprising a body portion, a plurality of gripping elements carried thereby for gripping a tool, rotatable means engaging said gripping elements for moving them into loose engagement with the tool, said rotatable means being capable of limited longitudinal movement, a rotatable sleeve surrounding said body portion and contacting with said rotatable means, said body portion being provided with an annular extension having its lower face arranged adjacent the upper face of said sleeve, one of said faces being provided with a cam groove, and an antifriction ball arranged in said groove and contacting with the other of said faces.

4. A chuck comprising a body portion, a plurality of gripping elements carried thereby for gripping a tool, rotatable means engaging said gripping elements for moving them into loose engagement with the tool, said rotatable means being capable of limited longitudinal movement, a rotatable sleeve surrounding said body portion and contact-

ing with said rotatable means, said body portion being provided with an annular extension having its lower face arranged adjacent the upper face of said sleeve, said faces being provided with oppositely arranged convolute cam grooves, and antifriction balls arranged in said grooves.

5. A chuck comprising a body portion, a plurality of gripping elements carried thereby for gripping a tool, rotatable means engaging said gripping elements for moving them into loose engagement with the tool, said rotatable means being capable of limited longitudinal movement, a rotatable sleeve 10 surrounding said body portion and contacting with said rotatable means, said body portion being provided with an annular extension having its lower face arranged adjacent the upper face of said sleeve, said 15 faces being inclined with respect to each and provided with oppositely arranged convolute grooves, and antifriction balls arranged in said grooves to move said gripping elements into firm engagement with 20 the tool upon rotation of said sleeve.

6. A chuck comprising a body portion, a plurality of downwardly converging gripping elements slidably mounted therein and adapted to be clamped about a tool, said elements being provided with relatively high 30 pitched threads, a rotatable ring having internal threads engaging the threads on said gripping elements, said ring being capable of limited longitudinal movement, a slideable and rotatable sleeve surrounding said 35 body portion above said ring, antifriction balls disposed between said ring and said sleeve, a cap carried by said body portion and having its lower face arranged adjacent the upper face of said sleeve, said 40 faces being relatively inclined and provided with oppositely convoluted grooves, and antifriction balls arranged in said grooves at their points of intersection.

In testimony whereof I affix my signature 45 in presence of two witnesses.

HARRY R. McCONNELL.
